UNITED STATES PATENT OFFICE.

WILLIAM H. MINER, OF CHAZY, NEW YORK.

MEANS FOR SUPPORTING FACE-PLATES OF VESTIBULE-CARS.

1,175,975.

Specification of Letters Patent. Patented Mar. 21, 1916.

Application filed May 4, 1914. Serial No. 836,159.

To all whom it may concern:

Be it known that I, WILLIAM H. MINER, a citizen of the United States, residing at Chazy, in the county of Clinton and State 5 of New York, have invented a certain new and useful Improvement in Means for Supporting Face-Plates of Vestibule-Cars, of which the following is a full, clear, concise, and exact description, reference being had 10 to the accompanying drawings, forming a part of this specification.

My invention relates to improvements in means for supporting face plates and parts connected thereto in railroad passenger cars.

15 My invention is an improvement upon that disclosed in my Patent No. 1,070,054, issued August 12, 1913.

The object of my invention is, to provide a simple means for supporting the face plate 20 and the parts connected thereto in railroad cars. I accomplish this object by securing brackets to the ends of the car body, to which brackets rods are secured to connect said brackets to the face plate, the said rods 25 being provided with resilient means, such as springs adapted to compensate for the movements of the face plate to which the rods are secured.

In the accompanying drawings forming 30 a part of this specification, Figure 1 is an end view of a car body of that type having an end vestibule, showing the supporting mechanism embodying my invention in position thereon. Fig. 2 is a partial cross section 35 taken on line 2—2 of Fig. 1. Fig. 3 is a partial vertical longitudinal section taken on line 3—3 of Fig. 1. Fig. 4 is a partial cross section taken on line 4—4 of Fig. 3. Fig. 5 is a vertical longitudinal section of 40 the end of a car and the diaphragm thereon showing a modified form of my supporting mechanism.

Referring to the drawings, the numeral 6 indicates a car body (only the end thereof 45 being shown in the drawing) and 7 the vestibule thereof, 8 the roof of the car, the numeral 9 indicating the upper deck thereof, and 10 the lower deck.

The numeral 11 indicates the hood, and 50 12 the end of the vestibule. A diaphragm face plate 13 is secured to the end of the vestibule, and surrounds the end vestibule opening 14. The lower ends 115—115 of the diaphragm face plate 13 are secured to the 55 face plate 15. Above the face plate is the foot plate 16. Buffer stems 17—17 are suit-

ably secured to the end plate 15, preferably to the rear face thereof, as indicated at the numerals 18—18. A vestibule diaphragm cover 19 is secured between the diaphragm 60 face plate and the body of the car. Piston rods 20 are secured to the rear face of the diaphragm face plate, the same being extended inwardly into the vestibule. Brackets 21—21 are attached to the car body, preferably near the top of the end of the vestibule, and to each of said brackets is connected a downwardly extended rod 22, each of said rods being secured at its lower end to a bracket 23. Each of the brackets 23 is 70 secured to the diaphragm face plate by suitable means, preferably the rivets 24—24. Each rod 22 is preferably in an upper section 75 25 and a lower section 26, the said sections being connected by suitable means, 75 preferably the screw coupling 27. Each upper bracket 21 is provided with an upper arm 28 and a lower arm 29, the same being spaced apart, and each being provided with a perforation 30 for the passage of a rod 80 22. The rod 22 intermediate the upper and lower arms 28—29 of the bracket 21 is provided with a shoulder 31 and a spring 32 seated between said shoulder and the upper arm 28, and a spring 33 seated between the 85 said shoulder and the lower arm 29. The lower bracket 23 is provided with a vertical opening 34 for the passage of the rod 22, the rod being provided above the bracket with a shoulder 35 and a spring 36 seated 90 between said shoulder and the bracket, and being also provided below the bracket with a shoulder 37, preferably formed by the washer 38 and the nuts 39—39, between 95 which shoulder and the bracket is seated a spring 40. The rods 22 serve to support the diaphragm face plate and the face plate 15 and the parts connected thereto, and prevent wear of the buffer stems; and it will 100 be apparent that the springs mounted in connection with the rods 22 will serve to permit a limited movement of the parts supported by the rods without permitting the weight of the diaphragm face plate and other parts to bear upon the buffer stems.

In the modification illustrated in Fig. 5, the numeral 45 indicates the end of a car body having a diaphragm face plate 46, a diaphragm cover 47 between the diaphragm face plate and the car body, a face plate 48 110 connected to the diaphragm face plate, a foot plate 49 supported thereon, buffer stems

50 rearwardly extended from the face plate at its lower end, piston rods 51 rearwardly extended from the face plate at its upper end, and means for supporting the face plate from the car body, comprising the rods 61, the upper brackets 52 secured to the car body, the lower brackets 53 secured to the diaphragm face plate, and the springs 54—54. Each of the brackets is provided with a vertical perforation 55 for the passage of the rod 61, the upper spring 54 being seated at its lower end against the upper bracket, and at its upper end against the nut-head 56 with which the upper end of the rod 61 is provided. The lower spring 54 is seated at its upper end against the lower bracket, and at its lower end against the nut 57 with which the rod 61 at its lower end is provided.

20 The arrangement in the modification differs from that shown in Figs. 1 to 4 inclusive of the drawings especially in this: that in the modified form the springs are employed only to cushion the downward movement of the diaphragm face plate, while in the other form illustrated in the drawings the springs are employed to cushion both downward and upward movement of the diaphragm face plate.

I claim:—

30 1. In a railroad car, the combination with a car body having a vestibule end and a vestibule diaphragm face plate, of means for supporting said face plate, said means including brackets secured to each face plate 35 near the bottom thereof on each side of the vestibule, brackets secured to the end of the car on each side of the vestibule and near the top thereof, a rod extending between each pair of brackets on each side of the vestibule, and a spring interposed between each

bracket and rod associated therewith, whereby the face plate is yieldingly supported and permitted to move in a vertical plane.

2. In a railroad car, the combination with a car body, of a diaphragm face plate, and means for supporting said face plate, said means including upper brackets secured to the end of the car body, lower brackets secured to the face plate, said brackets being arranged in pairs on opposite sides of the vestibule, a rod extending between each pair of brackets, shoulders adjacent the ends of said rods, and springs interposed between said shoulders and the brackets.

3. In a railroad car, in combination, a car body, a face plate, and means for supporting the face plate, comprising rods connected thereto, and brackets secured to the car body, each of said brackets being provided with an upper and a lower arm, a rod passing through said arm, the rod being provided with springs seated between said arms.

4. In a railroad car, a car body, a face plate, and means for connecting said face plate to the car body, comprising brackets, rods passing through said brackets, and springs to cushion the movement of the rod in reference to the bracket in either direction.

5. In a railroad car, a car body, face plate, and means for supporting the same, said means comprising rods, each of said rods being connected at one end to the car body, and at the other end to the face plate, and having resilient means interposed in each of said connections.

WILLIAM H. MINER.
